[57] CLAIM

The ornamental design for a radiotelephone, as shown and described.

DESCRIPTION

FIG. 1 is a front view of the radiotelephone showing my design;

FIG. 2 is a rear view thereof;

FIG. 3 is a side view thereof;

FIG. 4 is an opposite side view thereof;

FIG. 5 is a top view thereof;

FIG. 6 is a bottom view thereof;

FIG. 7 is a perspective view thereof;

FIG. 8 is a front view of an alternative embodiment of the radiotelephone showing my design;

FIG. 9 is a rear view thereof;

FIG. 10 is a side view thereof;

FIG. 11 is an opposite side view thereof;

FIG. 12 is a top view thereof;

FIG. 13 is a bottom view thereof; and,

FIG. 14 is a perspective view.

The broken lines shown in FIGS. 2 and 8-11 are for illustrative purposes only and form no part of the claimed design.
